CLAIM

The ornamental design for a garden lounger, as shown and described.

DESCRIPTION

FIG. 1 shows an angular perspective view of a garden lounger according to my new design;

FIG. 2 shows a front perspective view of the garden lounger shown in FIG. 1, the rear perspective view being a mirror image thereof;

FIG. 3 shows a front perspective view of the garden lounger shown in FIG. 1 in the unfolded condition;

FIG. 4 shows a top perspective view of the garden lounger shown in FIG. 1;

FIG. 5 shows a bottom perspective view of the garden lounger shown in FIG. 1; and,

FIG. 6 shows an enlarged fragmentary rightside perspective view of the garden lounger shown in FIG. 1.
